UNITED STATES PATENT OFFICE.

FREDERICK-GEORGE FISHER, OF BOSTON, MASSACHUSETTS, ASSIGNOR TO NATIONAL FOLDING BOX COMPANY, OF NEW HAVEN, CONNECTICUT, A CORPORATION OF NEW JERSEY.

DISPLAY-CARTON.

1,362,565.

Specification of Letters Patent. Patented Dec. 14, 1920.

Application filed March 8, 1920. Serial No. 364,049.

To all whom it may concern:

Be it known that I, FREDERICK-GEORGE FISHER, a citizen of the United States, residing at Boston, in the county of Suffolk 5 and State of Massachusetts, have invented new and useful Improvements in Display-Cartons, of which the following is a specification.

My invention relates to certain new and 10 useful improvements in collapsible or knock-down paper boxes, which may be shipped in their collapsed condition or stored until wanted for use when they may be readily constructed or folded into box shape by the 15 user, and has for one of its objects to provide a box of collapsible nature, which may be made from a single blank, so cut as to be economical of material and at the same time have all the parts of the box comprising 20 integral parts of said blank. A further object is to arrange a display flap integral with the box which may be turned back to display advertisement or the like printed thereon. A still further object of the invention 25 is to so construct an easel for support of the box that all of its parts may be made integral with the blank from which the box is formed.

In the accompanying drawings,—

30 Figure 1 represents the blank from which my collapsible box is made.

Fig. 2 shows the box in its first stage of formation with the two edges secured together.

35 Fig. 3 shows the same with the display flap turned down upon the bottom of box and showing the end flaps and end sections.

Fig. 4 is a perspective view of the box at one stage of its formation.

40 Fig. 5 shows the end sections bent into place with only the steps of bending the end flaps into place and turning the display flap into display position remaining to be accomplished.

45 Fig. 6 is a longitudinal section through the box showing the parts in operative position as a display receptacle and the easel in place.

50 Fig. 7 is a view in perspective of the lower end of the box, the walls being broken away to show in section the double construction thereof.

Fig. 8 is a perspective view of the box assembled showing the display flap turned to 55 operative position.

Fig. 9 is a perspective view of the under-side of the box.

In the drawings it will be assumed for purposes of illustration that the blank of which the box is to be formed is made of 60 cardboard. The blank comprises in a general way the following parts: bottom sections 14 and 15, side panels 25 and 26, end sections 16, 17, 18 and 19, end flaps 20 and 21, a display flap 22, an easel or supporting member 23, and a securing strip or lap 24. When formed into a box the sections 14 and 15 constitute a double bottom and the panels 25 and 26 form double side walls. The purpose of these double members will herein- 65 after appear.

In preparing a commercial product from the blank shown in Fig. 1 which will be ready to be made up in box form by the user, by simply folding the parts into place, I fold 70 the side panels upon their dividing lines A—A and B—B and unite the edge of inner bottom member 14 with the securing strip or lap 24 by any suitable means, as glue or paste, or by mechanical fasteners. The strip 75 24, as shown in Fig. 2 is slipped under the inner bottom member 14 and said bottom member is extended over the whole surface of said strip, so as to present a neat and finished appearance when the box is assembled. 80 As an article of manufacture, the device is 85 at this stage complete and ready for delivery to the user.

The article may be made up as a package 90 for goods in the following manner: The side panels are turned on lines X—X up at right angles to the bottom members, as shown in Fig. 4, forming the sides; the display flap is bent down on line C toward the bottom member 14, and the end pieces 16 and 17 are 95 bent on lines Y, Y, so as to overlap each other, as shown in Fig. 5. The end pieces are secured in this position by means of the end flap 20, which is bent up along the line D and then folded along the line E, so that 100 the portion 27 thereof fits on the inside of the box as finally constructed, the part of the flap to which the number 20 is applied then lying outside of the end members. This construction provides a four ply wall at 105 what may be termed the upper end of the box.

The opposite end of the box, which may be termed the lower end, is provided with a four ply wall made by first bending in the 110

end section 19, on the right hand line Z (Figs. 1 and 3), bending in thereagainst the end section 18, and folding the end flap 21 up and over the two end sections. The section 19 has a centrally located notch, and the portion 29 which folds inside of the box is shorter than the corresponding portion 27 of flap 20 and has a centrally located tab 31 extending therefrom, and adapted both with respect to location and shape to pass through the notch in section 19 and to lie between said section and section 18 when the box is completed, as shown in Fig. 6. The portion 29 of the flap 21 bears against the portions of section 19 on either side of the notch and with the portion 30 of the tab on the outside braces the same, and the flap itself is held in place by the tab inserted through the notch, as above described. In this way the parts coöperate to mutually lock each other in place and to hold the parts in assembled position. When this step in the assembling of the device is completed, the box is ready to serve as a container for goods.

25 In order to adapt the box to display the contained goods, I have provided my box with an easel-like support 23, which is formed by cutting an elongated strip or tongue from the outer bottom member 15. 30 This strip is severed from member 15 by cutting it along three sides and leaving it attached along one end only.

This strip is formed with a bending line F—F, or is otherwise adapted to be bent so as to be readily formed into an easel or support. The inner bottom member 14 is provided with an abutment tongue 32 integrally formed therewith by cutting on all but one side from the bottom member 14 40 and adapted to be bent downward to receive the end of the easel and hold the same in supporting position.

The purpose of the easel, as indicated above, is to raise one end of the box so that 45 the article therein contained will be the better presented to view, and in order that a legend or advertisement relating thereto may be presented advantageously therewith. The inner bottom member is provided with 50 an extension or display flap 22 which is adapted to be bent along the line C—C and again along the line K—K at a distance from line C—C equal to about the height of the end walls of the box over which the flap is 55 adapted to be bent, and to rest at an angle, such that it advantageously displays the legend or advertisement thereon.

Having described the construction of my box, I will now point out some of the advantages obtained by forming the box in this particular way. It will be observed, by reference to Fig. 1 of the drawings, that the blank from which the box is to be made up is all of one piece and that projecting portions are so arranged that the necessary

waste in cutting the blank from stock is as small as possible. The display flap 22 is located in such position that the cutting may be partly made out of what would otherwise be waste from the previous blank.

The parts, as stated above, are all integrally formed in a single blank, which is so cut and folded that a complete compact and strong box is formed with no separable parts to become detached from the rest of the box and consequently lost, no fastening devices are needed outside of those integral with the blank itself, with the exception of the strip 24 and the attached edge of the member 14, which are glued together.

The construction of my device, whereby the side walls and bottom of the box are doubled, enables me to make my box of comparatively thin material and yet produce a strong durable box. The end walls, being 85 composed of four plies of material, need no other reinforcement. An additional advantage of making my box with a double bottom is that by so doing, I can form the easel member 23 from the outer bottom member 90 and at the same time not destroy the box as a container, the abutment tongue 32 may be formed from the inner bottom member, which may be adapted to coöperate with said easel to hold it in supporting position.

95 The lower end sections and the associated flap is held in place by the interlocking arrangement, described above. A similar arrangement may be used at the upper end of the box but these parts are preferably held in place by means of the display flap, the portion between the lines C—C and K—K of which rest against the loose end of flap 27, when the box is in assembled position.

100 Another feature of my box is that when assembled, the same surface of the material appears on the display tab and all other external surfaces of the box. This enables me to make my box of material finished only 110 on one side, and print the advertising matter which may be applied all on one surface of the blank and in one impression.

Having thus explained the nature of my said invention and described a way of making and using the same, although without attempting to set forth all of the forms in which it may be made or all of the modes of its use, what I claim is:—

1. In a display box having sides and a 120 double bottom comprising inner and outer bottom members, end members, a supporting easel cut from said outer bottom member in integral union therewith at one end, and an abutment tongue formed in said inner bottom member adapted to coöperate with the end of said easel, to hold said easel in supporting position.

125 2. In a display box having sides, ends and a double bottom comprising inner and outer 130

- bottom members, a supporting easel cut from said outer bottom member and in integral union therewith at one end, and an abutment tongue formed in said inner bottom member and being adapted to underlie the end of said easel inserted between said tongue and the inner bottom member whereby to retain said easel in supporting position.
- 5 10 3. A display box having a bottom composed of two layers or plies of boxboard or the like, the outer ply having cut from its integral substance a tongue which remains united thereto at one end and is adapted to be folded or bent on a transverse line, and 15 an abutment tongue cut from the material of the inner ply and adapted to underlie and arrest the free end of the first named tongue and located in such a position that when so engaged with the free end, the first 20 named tongue will be held bent on the before mentioned bending line to project outwardly from the box bottom.

In testimony whereof I have affixed my signature.

FREDERICK-GEORGE FISHER.
